UNITED STATES PATENT OFFICE.

WILLIAM GLADER, OF CHICAGO, ILLINOIS, ASSIGNEE TO JAMES W. BRAINARD, OF PITTSBURGH, PENNSYLVANIA.

HOOP-MACHINE.

1,271,723.

Specification of Letters Patent.

Patented Sept. 2, 1913.

Application filed October 14, 1911. Serial No. 852,761.

To all whom it may concern:

Be it known that I, WILLIAM GLADER, a citizen of the United States, residing at Chicago, in the county of Cook and State of Illinois, have invented certain new and useful Improvements in Hoop-Machines, of which the following is a specification.

My invention relates to hoop forming machines and has particular reference to a 10 novel machine for forming a bead on one edge of a strip of metal to be used as a hoop, such machine being capable of forming a bead of any desired cross-section including a bead of circular cross-section, which latter 15 is considered to be preferable.

Heretofore, as far as I am aware, the formation of the bead on the edge of a hoop strip has been universally carried out by means of bending rolls, that is, the strip 20 has been passed through a series of bead forming rolls; the result being a bead which has no undeturned portion and which is in effect merely a bending back or bending over of one edge of the strip, the bent over 25 portion of course, having a slight curve. In addition to the unsatisfactory contour of the bead, and the comparatively slight advantage gained thereby there has been the additional disadvantage that in rolling the edge 30 to secure the turning of the bead the metal was slightly expanded thus elongating the edge having the bead. Unfortunately this elongation was on the wrong edge of the hoop, that is, the edge of the hoop having 35 the bead is always toward the smaller end of the barrel or keg. For this reason it was necessary to perform an additional operation whereby the hoop was stretched on the opposite edge with the consequent effect of 40 weakening the entire hoop. Another disadvantage of the rolling operation arises from the following conditions: It is desirable, in fact necessary that the hoops should be cut and punched prior to the beading operation. Furthermore, it will be understood 45 that during these various operations in connection with the rolling of the bead the metal is stretched and restretched owing to 50 irregularities in gage of the metal strips with the result that the final hoop when riv-

eted and while being riveted is warped and sometimes entirely useless.

With this general explanation of the difficulties encountered with the formation of the bead on a flat metal strip by the rolling process I will proceed to a description of advantages gained by the mechanism herein shown and described. First, in a machine of the present construction the bead is formed simultaneously throughout the 55 length of the metal strip, that is, the entire bead is turned up in one operation by stamping or pressing. The remainder of the metal strip is meanwhile rigidly held. Second, no elongation of the beading edge is encountered even though there be a variation in the gage of the metal, in fact, there will be a slight contraction, which contraction is desirable. Third, to provide a machine which while in a sense intermittent in action will 60 permit of the development of a speed of production equal to, if not greater than the rolling operation. Fourth, to provide a machine which will automatically prevent the insertion of more than one metal strip at a 65 time. Fifth, to provide a machine having novel forming dies. Further and more particular objects will appear hereinafter.

My invention will be more readily understood by reference to the accompanying 70 drawings wherein—

Figure 1 is a side elevation of a machine constructed according to my invention. Fig. 2 is also a side elevation taken from the reverse of the machine shown in Fig. 1. Fig. 85 3 is a top plan. Fig. 4 is an end elevation of the receiving end of the machine. Fig. 5 is a partial section on the line 5—5 of Fig. 1. Fig. 6 is an elevation of the discharging end of machine. Fig. 7 is an enlarged detail front elevation of the discharge end of machine showing the coiling mechanism. Fig. 8 is a plan of the same mechanism. Fig. 9 is a plan of the feed end of machine showing the clamp and automatic stop. Fig. 95 10 is a section on the line 10—10 of Fig. 9. Fig. 11 is a detail plan view of a fragment of the dies, clamps and rolls at the delivery end of machine. Fig. 12 is an enlarged detail, partly in section, showing the feed rolls, 100

clamp and die. Fig. 13 is a detail sectional elevation on a still further enlarged scale showing the dies and clamps with a hoop held between the clamps and the die about 5 to advance to form the bead. Figs. 14, 15 and 16 are end elevations showing respectively a plain band of steel, a hoop strip having an initial bend and a completed hoop strip with a perfect bead formed thereon, 10 and Fig. 17 is a plan of a length of metal formed into a hoop strip having the bead thereon.

Referring more particularly to the drawings it will be seen that on the frame composed of standards 20 and intermediate and upper connecting members 21-22 and 23, I mount in bearings 24, 25 and 26 a longitudinally extending cam shaft 27. Power is supplied for the operation of this shaft by 15 means of the large gear 28, with which meshes a pinion 29, keyed to a shaft 30. Also keyed to the shaft 30 is a bevel gear 31, which in turn meshes with a bevel pinion 32 rigid with power shaft 33, which 20 shaft carries tight and loose pulleys 34 and 35. Mounted on the cam shaft 27 is a plurality of cams. There being four sets of such cams and as each set is a duplicate of the other I will describe but one thereof. The 25 cam 36 is keyed to the shaft 27 and is arranged to cause the oscillation of a lever 37, fulcrumed at 38 on a standard 39 which is in turn rigidly secured to the upper connecting member 22. This lever and 30 its connecting parts causes the reciprocation of the upper clamping member later to be described. A cam 40 is also keyed to the shaft 27 and is arranged to cause the oscillation of rocker 41, fulcrumed on a shaft 35 42 and arranged to cause the reciprocation of the bead forming die plate, which also 40 will be later described.

In order to provide for the feeding of the strip of metal into the machine, I provide 45 a plurality of rolls 43, 44. These rolls being pinned to shafts 45 and 46, shaft 46 having on one end the bevel pinion 47 meshing with the gear 48 keyed to shaft 30, also on shaft 46 as shown in dotted lines 50 in Fig. 2 is a pinion 49 meshing with a further pinion 50 and keyed to shaft 45. The shaft 46 on its end adjacent to the roll is mounted in bearing 51, which is vertically adjustable by means of a set bolt 52. The 55 shaft 45 is held at the roll end in a bearing 53, which is arranged for limited vertical movement in guides 54 against a compression spring 55. This is best shown in Fig. 12.

60 I will now describe my novel feeding mechanism by means of which the bands of steel are fed into the machine singly. This includes a bracket 56 secured to one of the standards 20 and carrying roll housings 57 and 58 within which are carried the rolls

59 and 60 arranged to cause the initial bending or edge turning as shown in Fig. 15. These rolls are connected to the power shaft 33 by means of a square shaft 61 and suitable square couplings loosely fitted. 70 This is arranged in a well known manner to admit of a vertical adjustment of the rolls without realinement of shaft. The two rolls 59 and 60 are geared together by means of the gears 62. A sprocket is 75 mounted on the lower roll shaft and by means of a sprocket chain 63 and a further sprocket wheel mounted on the shaft 64 motion is transmitted to the lower of two timing rolls 65 and 66. These two rolls are arranged for operation in unison by means of intermeshing gears 67. The upper roll 66 is arranged for limited vertical movement by reason of its being mounted in bearings carried in one end of a rocker 80 68 pinned to a stub shaft 69 mounted in a bearing 70 projected upwardly from the bracket 56. To the outer end of shaft 69 is pinned a lever 70 having a link or rod 71 connected thereto, which link has at its 85 lower end a threaded portion on which adjusting nuts 72 are placed. A lever 73 having a projecting lug 74 is provided with an aperture through which the rod 71 projects. It will be seen that the lever 73 is fulcrumed 90 at 75 to a portion of the standard 20 and at its free end is provided with an anti-friction roll 76 contacting with a cam 77 rigidly secured to the cam shaft 27. Upon 95 the rotation of the cam member the link 71 and its associated parts are adapted to be moved vertically, the anti-friction roller 76 on one end of the lever 73 being held in engagement with the cam 77 by a contractile spring 78 secured by its ends to the lever 100 and a portion of the frame.

On the lever 68 and projecting into line with its supporting shaft is an extension having an aperture therethrough within which a stop piece 79 held in adjusted position by means of a set bolt 80. A guide trough 81 is provided and through this trough I arrange an opening 82 through which the stop member 79 is projected. It will thus be seen that the upper timing rolls 66 and the stop member 79 operate contrariwise; that is, when the rolls 65-66 are in feeding engagement stop 79 is elevated and vice versa. It will also be seen that the elevation of the stop is momentary only. That is, just a sufficient length of time elapses to permit of the timing rolls to feed a hoop blank into the bite of the forming rolls 59-60. The stop 79 will then drop and ride upon the top of the in-feeding hoop blank. In this manner it will be seen that the operator cannot by any means feed a hoop blank into the machine until the preceding hoop blank has begun its passage out of the machine. He may 110 115 120 125 130

project the hoop between the feed rolls 65-66 which are at that time separated and to a point against the edge of the stop 79, where the hoop blank will remain until the stop 79 is raised, the roll 66 is lowered and the hoop blank is fed into the bite of the next consecutive rolls.

45 I will now describe the clamp by means of which the strip is securely held while the pressing or stamping of the die takes place. As heretofore described the lever 37 which is mounted on the cross member 22 carries at its outer end by means of a pin 83, an adjustable link 84, connected to apertured lugs 85 integral with the upper clamping member 86. This clamping member is held in proper relation by means of projecting bolts 87 seated in slots in the clamp. In order to provide for the reception of different widths of hoop blanks I secure to the lower edge of the clamping member 86 a hard metal die 88. This member 88 has a hardened steel insert 89 provided with a groove 90 near its lower edge within which the bead is formed. This removable member 88 is secured to the clamping member 86 by means of the lag bolts 91. The lower clamping member 92 rests in a recess in the cross member 21 and is held in adjusted transverse position by means of clamp 93 and set bolts 94. Within this lower clamping member I seat a square strip 95 to provide a wearing surface for the incoming strips of metal also as a stop against the thrust of the bead forming die. This strip is made square in order that it may be turned as it becomes worn, thereby providing four wearing surfaces for the same piece of metal. It will be seen by reference to Fig. 13 that the lower die extends to a point well beneath the upper die and has a cut-away portion 96 within which the projection or shelf of the bead forming die extends when the die is advanced.

46 The bead forming die of my invention comprises a plate of hardened steel extending from end to end of machine; although for convenience this may be made in sections if desired. This die is composed of a body portion 97 having a lateral shelf 98-99 on each edge. Midway between the two faces of the die 97 and the base of the shelves 98-99 I provide semi-circular grooves 100-101. These are in reality the bead-forming grooves and, as shown in Fig. 13, cause the strip of metal to be upset and turned over on itself. The two edges are identical in order to provide two dies for the same piece of metal. This die is held in position by means of a clamp 102 suitably bolted to the reciprocating die plate 103. If preferred the die member 97 may be seated on a liner 104 for convenience. This part may be renewed if desired in order to correct or change the alignment of the die. The

die plate 103 is supported on suitable slide-ways 105 formed as a part of the standards 20 and is guided by the lower shafts 46 of the feed rolls. This die plate is held in retracted position by means of a plurality of coiled contractile springs 107 as shown in Fig. 3. The reciprocation of die plate is brought about by the oscillation of the arms 41 having the lever 41^a projecting therefrom. For convenience I provide wear plates 108 on the contacting parts.

On the delivery side of machine I arrange 80
housings 109--110 carrying rolls mounted
in the usual manner. There are two sets of
rolls in order to provide for carrying the
hoop blank away from the machine a suffi-
cient distance to permit of coiling, if but
one set of rolls were used this set of rolls
might be removed so far that a short hoop
blank might not be engaged thereby when
being delivered from the machine. The
rolls contained in housings 109--110 are
geared together and arranged for operation
in unison by means of sprockets and chain
111. On the outer housing 110 I mount a
bracket 112 carrying a casting 113 within
which a threaded shaft 114 is held. This
shaft is provided with a crank 115 and on
the free end of the shaft is mounted a block
116 having a portion cut-off diagonally. 90
Hinged to the casting 113 is a swinging
guide plate or strip 117 held against the
diagonal portion of the block 117 by the
spring 118. It will be seen that by rotation
of the shaft 114 the block 116 is advanced
or retracted, thus changing the angle of in-
clination of the guide 117. As the hoop
blank is fed from the rolls 109--110 its ad-
vance end contacts the guide 117 and a bend
is given to the hoop blank. The extent of 100
bend or size of the circle is controlled by the
inclination of the guide 117. As will be
seen from Fig. 8 the upper rolls carried in
the housings are grooved as at 119 to ac-
commodate the previously formed bead on 105
the hoop blank. 110

It will be understood that the feed rolls throughout the machine as heretofore described are continuously in rotation and that therefore, a stop must be provided in order to locate the hoop blank in position to be clamped and receive the bead. Such a stop is shown in Figs. 1 and 3. The operation of this stop is much the same as that described in connection with the stop 79. A cam 120 is mounted on the cam shaft 27, which cam operates a lever 121 fulcrumed at 122 and operating a link 123 which link is pivoted at 124 to a casting 125 having a dove-tail therein fitting a corresponding projection on a portion of the frame. A stop member 126 is secured to the member 125 by means of bolt 127. It will be seen that by properly timing the cam that the stop will be lifted to permit the escape of the hoop blank with its bead to 130

the delivery rolls and will immediately after the escape of the hoop blank drop back and ride thereon ready to drop off the receding end of the out-going hoop blank and into 5 the path of the incoming hoop blank.

The operation of my machine is as follows: Power is applied and the train of rolls are put into operation. A strip of metal cut to suitable length is placed in the 10 guide-trough, being passed between the rolls 65-66, which are then separated and being arrested by the stop 79 which is then in depressed position projecting through the opening 82. By means of the cam 77 stop 15 79 is lifted and the rolls 65-66 are brought into feeding engagement with the strip of metal which is fed forward between the bending rolls 59-60. As soon as these rolls engage the strip the cam operates to lower 20 the stop and separate the timing or in-feeding rolls 65-66, the forward feeding of the strip being accomplished by the preliminary bending rolls. The strip advances, passing successively between the several pairs of 25 rolls until its leading end encounters the stop 126. Practically simultaneously with the arresting of the strip the clamp is depressed, the train of rolls 43-44 turning idly on the surface of the strip. The die 30 plate carrying the die 97 is then advanced under the action of its cam, turning the bent edge of the metal over and completing the formation of the bead by a single continuous movement. During the bending, feeding 35 and bead-forming operations on the engaged strip the operator places in the receiving-end of the machine another strip which however, is held back by the stop 79. Instantly when the stop 126 is raised, the 40 pressure of the clamp is released and the beaded strip is fed out of the machine. Simultaneously the stop 79 is raised and a new strip is fed into the machine.

It is obvious that while the several instrumentalities herein described are preferably conjointly used, some of them may be dispensed with, or instrumentalities of a different form or construction substituted therefor. For example—the timed feeding 45 rolls might be dispensed with and the strip of metal fed directly into the grasp of the bending rolls; or the preliminary bending rolls might be omitted or be substituted by a pair of dies for slightly up-turning the 50 edge of the metal so as to insure the action of the bead forming dies. So too, the stop might be dispensed with and the train of feeding rolls thrown out of action during 55 the operation of the bead forming dies.

60 I claim:

1. In a beading machine, the combination with means for feeding a strip of metal lengthwise, means for clamping the strip, and a stop engaging with one side edge of 65 the strip to prevent sidewise movement

thereof when held by the clamping means, of means for curling one marginal side edge of the strip to form a bead extending throughout the length thereof, said curling means including a horizontally reciprocating die having a bead forming cavity therein to engage and curl the edge of the strip in forming the bead thereon, substantially as described. 70

2. In a beading machine, the combination 75 with means for feeding a strip of metal lengthwise, means for curling one marginal side edge of the strip, means for clamping the strip, and a stop engaging one marginal side edge of the strip when being clamped 80 to prevent sidewise movement thereof, of a horizontally reciprocating die engaging with and curling the partly curled opposite marginal side edge of the strip to form a bead, substantially as described. 85

3. In a beading machine, the combination 90 with means for feeding a strip of metal lengthwise, means for clamping the strip of metal, means engaging one marginal side edge of the strip to prevent sidewise movement thereof when between the clamping means, of a horizontally reciprocating die having a bead forming cavity therein, said cavity engaging with the opposite edge of the strip to curl said opposite edge and form 95 a bead on the strip when the die is reciprocated, and means for reciprocating said die, substantially as described.

4. In a beading machine, the combination 100 with a bead forming mechanism having 105 means for clamping the top and bottom surfaces of strips of metal, and means engaging with one side edge of metal strips held between the clamping means to curl said edge into a bead, of means for successively feeding strips of metal to said clamping means, and means for partly bending the said edge of the strips into beaded form during the forward movement thereof into position between the clamping means, substantially as 110 described.

5. In a beading machine, the combination 115 with feed rolls arranged to deliver strips of metal lengthwise, bending rolls arranged to curl one marginal side edge of the strip during the lengthwise movement of said strips, clamping means into which said partly beaded strips are fed by said rolls, and bending means alongside said clamping means arranged to engage with and curl the bent edge of said strips into a bead extending throughout the length of said strips; substantially as described. 120

6. In a beading machine, the combination 125 with feed rolls adapted to deliver metal strips lengthwise, bending rolls arranged to engage with and bend one side edge of said strip while passing lengthwise between said rolls, means for clamping said partly beaded strips into which the strips are delivered 130

by the feed rolls, and a reciprocating die engaging with the bent edge of the strips held by the clamping means to curl the bent edge of the strip into a hollow bead, substantially as described.

7. A beading machine comprising in combination a feeding device, means for preliminarily bending a strip of metal, means for advancing such strip of metal between the clamping mechanism of the machine, mechanism for clamping said strip, and means for simultaneously completing a bead on the bent edge of the strip throughout the entire length of said strip while held by said clamping mechanism, substantially as described.

8. A beading machine comprising in combination a base, a timed stop on the feed end of said machine, rolls arranged to give said strip a preliminary bend and advance the strip into the machine, means for temporarily arresting and clamping said strip and means for simultaneously forming a bead throughout the entire length of said strip, substantially as described.

9. A beading machine comprising in combination a base, timed feeding attachments, bending rolls and feeding rolls, clamping means arranged to clamp the entire length of metal to be treated, one edge of the metal being left free, a reciprocating die arranged to form a bead on the free edge of said strip of metal, and means for unclamping said dies and delivering said strip of metal from said machine, substantially as described.

10. A beading machine comprising in combination a base, timed feeding means,

means for preliminarily bending a strip of metal, means for clamping the strip of metal throughout its length, continuously operating strip feeding rolls, and means for simultaneously forming a bead throughout the length of metal held by said clamp, substantially as described.

11. A beading machine comprising in combination a base, a pair of intermittently operating feed rolls, and a stop, said stop and said feed rolls being arranged at the feeding end of the machine, continuously operating feed rolls in the machine, clamping means arranged to act upon the entire length of metal held within the machine, said continuously operating rolls meanwhile slipping on the surface of said strip, and an automatically actuated stop arranged to arrest a strip of metal at the proper point to be grasped by said clamps, substantially as described.

12. A beading machine comprising in combination a base, intermittently actuated feeding means, bending means and a clamp, said clamp having a removable metal contacting member, a pair of dies, one of which is removable and reversible, means for actuating one of said dies whereby a bead is formed throughout the length of metal held by said clamp, and means for feeding said length of metal from said machine, substantially as described.

WILLIAM GLADER.
